US00D771981S

(12) **United States Design Patent** (10) **Patent No.:** **US D771,981 S**
(45) **Date of Patent:** **** Nov. 22, 2016**

(54) **DESK**

(71) Applicant: **Varidesk, LLC**, Coppell, TX (US)

(72) Inventors: **Daniel G. Flaherty**, Irving, TX (US);
David Patton, Flower Mound, TX (US)

(73) Assignee: **Varidesk, LLC**, Coppell, TX (US)

(**) Term: **14 Years**

(21) Appl. No.: **29/512,877**

(22) Filed: **Dec. 23, 2014**

(51) LOC (10) Cl. **06-04**

(52) U.S. Cl.

USPC **D6/655**; D6/707.15

(58) **Field of Classification Search**

USPC D6/655, 662, 644, 654, 653.17, 653.14,
D6/653.1, 653.11, 707.15; D14/305;

108/139, 95–96, 141

CPC A47B 3/00; A47B 3/002; A47B 41/00;
A47B 41/02; A47B 21/00; A47B 21/02;
A47B 17/02

See application file for complete search history.

(57) **CLAIM**

The ornamental design for a desk, as shown and described.

DESCRIPTION

FIG. 1 is a front-right perspective of an embodiment of the desk according to the claimed design shown in a lowered position;

FIG. 2 is a front view of the desk of FIG. 1;

FIG. 3 is a rear view of the desk of FIG. 1;

FIG. 4 is a left side view of the desk of FIG. 1;

FIG. 5 is a right side view of the desk of FIG. 1;

FIG. 6 is a top view of the desk of FIG. 1; and,

FIG. 7 is a front-right perspective of the desk of FIG. 1 shown in a raised position.

The features shown in broken lines represent portions of the desk which form no part of the claimed design.

1 Claim, 7 Drawing Sheets
